BURGLAR ALARM

Peter John Doodson, De Koppela 133,
Eindhoven, Netherlands

Filed May 4, 1971, Ser. No. 140,311

Claims priority, application Switzerland Nov. 9, 1970

Term of patent 14 years

Int. Cl. D29—99

U.S. Cl. D72—1 A

FIG. 1

FIG. 2

FIG. 3

FIG. 4

FIG. 5

FIG. 6

FIG. 7

FIG. 1 is a perspective view of the burglar alarm showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof;

FIG. 7 is a bottom plan view thereof.

The apertures are partially shown in FIGS. 1 and 2 for convenience of illustration, it being understood that they continue uniformly within the areas inclosed in broken lines.

I claim:

The ornamental design for a burglar alarm, as shown and described.
